(57) **CLAIM**

The ornamental design for a personal pill organizer and identifier, as shown and described.

DESCRIPTION

FIG. 1 is a front, top and left side perspective view of a personal pill organizer and identifier showing my new design; FIG. 2 is a rear, top and left side perspective view thereof; FIG. 3 is a front elevational view thereof taken in the direction of arrow 3 in FIG. 9;

FIG. 4 is a rear elevational view thereof taken in the direction of arrow 4 in FIG. 9;

FIG. 5 is a top view thereof taken in the direction of arrow 5 in FIG. 9;

FIG. 6 is a bottom view thereof taken in the direction of arrow 6 in FIG. 9;

FIG. 7 is a left side view thereof taken in the direction of arrow 7 in FIG. 9;

FIG. 8 is a right side view thereof taken in the direction of arrow 8 in FIG. 9; and,

FIG. 9 is a front, top and left side perspective view, identical to FIG. 1, with the directional arrows included.

It is to be understood that any portion of any figure shown in broken lines are for environmental purposes only and form no part of the claimed design.
